4,889,285 A 12/1989 Locko
4,913,350 A 4/1990 Purzycki

FIG. 2 is a front elevation view thereof, the rear, right side, and left side elevation views being identical thereto;

FIG. 3 is a top plan view thereof;

FIG. 4 is a bottom plan view thereof;

FIG. 5 is a perspective view of a second embodiment of a reed diffuser and light source, having opaque inner and outer vases;

FIG. 6 is a front elevation view thereof, the rear, right side, and left side elevation views being identical thereto;

FIG. 7 is a top plan view thereof; and,

FIG. 8 is a bottom plan view thereof.

The broken lines depict environmental subject matter only and form no part of the claimed design.
